John A. Bonham
ATTORNEY

UNITED STATES PATENT OFFICE.

WILLIAM AUBERLIN, OF NORTHLFIELD, OHIO.

MEANS FOR MOORING AIRSHIPS TO MOORING MASTS.

Application filed August 1, 1927. Serial No. 209,830.

The invention herein described relates to an improved means for mooring an air-ship to a mooring mast.

It is common knowledge that under the prevailing conditions an air-ship cannot be left moored to a mast when a strong wind or gale is blowing, for fear of great damage being done to the air-ship. When such a condition exists the ship is cut loose from the mooring mast and takes the chance of successfully riding out the storm, oftentimes it is necessary to remain in the air hours before the storm abates to permit a safe landing. This is a serious handicap in the present day operation of lighter than air air-ships not only from the standpoint of absolute destruction of such a ship, but also making it impossible to maintain any kind of a schedule if regular trips are contemplated. The ship is subjected too much to the caprices of the wind. The factors that are responsible for the failure to safely moor a ship to the mooring mast, without having its nose pulled off when subjected to undue stress or pull, is due to its enormous size and that no adequate provisions are provided to make it perfectly safe for an air-ship to ride out a storm when moored to the mooring mast.

The present invention is designed to remedy these handicaps, and is illustrated in the accompanying drawings, in which Fig. 1 is a side view of an airship provided with the invention. Figs. 2 and 3 are details in section of parts of the device.

The airship is indicated as a whole at 6 and may be of any suitable construction in general. Its frame is provided with a plurality of tubes 7, which may be added to the frame or form a part of the longitudinal members thereof, as desired. They are preferably placed an equal distance apart and extend from the nose to the tail of the ship, being curved to agree with the form of the ship. The tubes are open at both ends, where they are securely fastened together. Extending through each tube is a cable 10 and the tubes act as guides for the cables which move therein and keep them properly spaced around the ship. At each end of the

ship the cables are fastened to rings 13 and the one at the nose is made fast to the mooring cable 11. An additional ring may also be provided for a ground cable 14, to be used for pulling the nose of the ship down; and the cable 12 attached to the ring at the rear for a like purpose.

Instead of tubes for the cables, the girders of the ship may be provided with V-shaped grooves or other guides for the cables to work in.

The tubes are preferably provided, especially at the points of greatest curvature, with enlarged couplings or casings 8 containing rollers 9 over which the cables pass, to permit free movement thereof.

By the means described it is possible to safely moor an air-ship to a mooring mast and let it ride out a gale, the action being as follows.

When the ship is moored to the mast, the cables being fastened to the mooring ring which in turn is fastened to the mooring cables, any excessive air pressure exerted on the nose of the air-ship will cause a backward movement of ship and when this happens the slack of the cables will be taken up, this action will make the cables grip, the harder the wind blows the tighter the grip will be. This stress or grip will spread the stress or strain exerted by the wind over the entire frame work structure. It can readily be appreciated that no particular part of the structure will be subjected to any undue stress or strain. I do not limit myself to any particular number of tubes and cables, the more there are used the greater the percentage of safety. On account of the curvature of the air-ship nose a number of rollers or pulleys are placed in each tube to provide freer movement for the cables at the various points. Ropes or chains may be used but are not so reliable or firm as steel cables.

I claim:

1. An air-ship provided with guides extending from nose to stern, and cables in said guides, said cables being adapted for connection to a mooring mast or the like.
2. An air-ship provided with spaced

- guides near the surface thereof and extending from nose to stern, and cables extending in said guides from nose to stern and all connected at their ends to mooring devices.
5. 3. An air-ship provided with a plurality of curved tubes extending from bow to stern, and cables loosely confined in said tubes, and connected at their ends to mooring devices.
4. An air-ship provided with a plurality of spaced longitudinally extending tension

devices loosely confined therein and connected at one end to a mooring device.

5. An air-ship provided with a plurality of spaced cables extending from end to end near the surface thereof and loosely confined to permit contraction, said cables being connected at one end to a mooring device. 15

In testimony whereof, I do affix my signature.

WILLIAM AUBERLIN.
